FLAG

Mann E. Jacob, 1222 W. Flora St., Philadelphia, Pa.

Filed July 28, 1960, Ser. No. 61,612

Term of patent 14 years

(Cl. D29—17)

The figure is a plan view of a flag showing my new design;

The flag is of conventional thickness and the reverse of the flag is a mirror image of the side shown in the figure.

The dominant features of the design reside in the combination on the striped flag disclosed of a field of stars wherein some of the stars extend across the uppermost stripe, a faced sunburst and double face profile within the field of stars, and a thin stripe on the staff-side that extends from below the uppermost stripe to the top of the bottom stripe, all as shown.

The drawing has been lined for color.

I claim:

The ornamental design for a flag, substantially as shown and described.
